UNITED STATES PATENT OFFICE.

THOMAS DE WITT RIVERS, OF LAKE CITY, FLORIDA.

FENCE-STRETCHING CLAMP.

1,184,021.

Specification of Letters Patent. Patented May 23, 1916.

Application filed July 23, 1915. Serial No. 41,560.

To all whom it may concern:

Be it known that I, THOMAS DE WITT RIVERS, a citizen of the United States, residing at Lake City, in the county of Columbia and State of Florida, have invented 5 a new and useful Fence-Stretching Clamp, of which the following is a specification.

The present invention appertains to fence clamps used for stretching the wire strands, 10 and aims to provide a novel and improved appliance of that character.

It is the object of the invention to provide a fence stretching clamp comprising a unique assemblage of the component parts, 15 whereby the wire strands may be conveniently applied to the clamp, and so that when the clamp is pulled by the stretching mechanism, the wire strands will be tightly gripped to prevent slippage.

It is also within the scope of the invention to provide a fence stretching clamp of the nature indicated, which is comparatively simple and inexpensive in construction, as well as being convenient, efficient and thoroughly practical in use. 20

With the foregoing and other objects in view which will appear as the description proceeds, the invention resides in the combination and arrangement of parts and in 25 the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a side elevation of the improved fence clamp, a portion thereof being 40 shown in section. Figs. 2 and 3 are sectional views taken on the lines 2—2 and 3—3, respectively, of Fig. 1.

In carrying out the invention, the clamp embodies three parallel bars 1, 2 and 3, constructed of wood, metal or other suitable material. A series of bolts or equivalent elements 4 are slidable through the intermediate bar 2, and their heads 5 are arranged 45 at one side to bear against the outer side of the clamping bar 1. The bar 1 is provided with a series of slots 6 receiving the bolts 4 and extending to one edge of the said bar, whereby the said bar may be readily applied to and removed from the bolts 50 4 when the clamp is applied to and removed

from the wire strands, respectively. The bolts 4 are attached rigidly to the bar 3, by means of nuts 7 threaded upon the bolts and embedded in the inner side of the bar 3, and nuts 8 threaded upon the ends of the bolts and bearing against the outer side of said bar 3. The nuts 7 and 8 thus clamp the bar 3 therebetween and fasten the bolts 4 rigidly to said bar. The bar 2 is slidable upon the bolts between the bars 1 and 3. 60

The adjacent sides of the bars 1 and 2 are provided with longitudinal corrugations 9 whereby the wire strands disposed between the said bars will be firmly gripped therebetween when the bar 2 is forced 65 toward the bar 1, as will hereinafter more fully appear.

As a means for gripping the wire strands when the clamp is pulled by the stretching or draft-creating mechanism, a plurality of longitudinally spaced wedges 10 are disposed slidably between the bars 2 and 3, the wedges 10 being arranged transversely of the bars, and the forward or smaller ends of the wedges are fastened to a draft bar 70 12 parallel with the bars 1, 2 and 3. The adjacent sides of the bars 2 and 3 are provided with transverse channels or grooves 11 for partially receiving the wedges 10, and the bottoms of the channels 11 of the bars 3 are disposed obliquely or diagonally to properly accommodate the oblique or diagonal faces of the respective wedges 10. The draft bar 12 is provided with an opening 75 13 for the engagement of a chain or other part 14 of the stretching mechanism (not shown), whereby the bar 12 is pulled for drawing the remainder of the clamp therewith during the stretching operation. 80

In operation, the wire strands may be 90 readily applied to the clamp, by slipping the bar 1 laterally out of engagement from the bolts 4, which allows the strands to be conveniently and properly placed against the corrugated side of the bar 2. The bar 1 is then replaced by slipping it upon the bolts 4 under the heads 5 thereof, the wedges 10 having been moved rearwardly to allow the bars 1 and 2 to separate sufficiently, 95 whereby the bar 1 may be properly placed upon the bolts without interference. Now, when the strands are properly arranged and applied, the draft bar 12 is drawn forward by the stretching mechanism, which will 100 pull the wedges 10 therewith. The wedges 105 110

10 working between the bars 2 and 3, will separate them, until the bar 2 is moved sufficiently toward the bar 1 for firmly gripping the strands, in which event, the bars 5 1, 2 and 3, will be pulled forward with the wedges. In this manner, the strands are properly gripped before they are drawn taut, and this prevents the slippage or displacement of the strands during the stretching operation. The greater the draft, the greater will be the gripping action upon the wire strands, so that the strands cannot 10 pull loose. The present clamp is therefore of obvious advantage in stretching wire 15 fences, and is convenient and efficient in use. The bolts 4 are preferably disposed immediately above and below the respective wedges 10, to reduce to a minimum, the tendency of the bars 1, 2 and 3, being bent out of shape 20 or broken, by the action of the wedges.

Having thus described the invention what is claimed as new is:

1. A clamp comprising three bars, a wedge disposed slidably between two of said 25 bars, one of said bars and the third bar forming clamping bars, and means connecting the third bar and the other of the first mentioned two bars.

2. A clamp comprising three bars, members attached rigidly to one of said bars and slidable through another bar, a wedge fitting slidably between the said two bars, said members being engaged to the third bar and the second mentioned and third bars co- 35 operating to provide clamping bars.

3. A clamp comprising three bars, bolts secured rigidly to one bar and slidable through another bar, the third bar being detachably engaged to said bolts and co-operating with the second mentioned bar to 40 provide clamping means, and wedges dis-

posed slidably between the two first mentioned bars.

4. A clamp comprising three bars, bolts secured rigidly to one bar and slidable 45 through another bar, the third bar being detachably engaged to said bolts and co-operating with the second mentioned bar to provide clamping means, wedges between the two first mentioned bars, the bolts being 50 arranged immediately adjacent the respective wedges, and a draft bar attached to the smaller ends of the wedges.

5. A clamp comprising three bars, bolts secured rigidly to one of them and slidable 55 through another, the third bar having slots extending to one edge thereof, and being detachably engageable with the bolts, the bolts having heads to bear against the third mentioned bar, and wedges slidable transversely 60 between the two first mentioned bars.

6. A clamp comprising three bars, bolts secured rigidly to one of them and slidable through another, the third bar having slots extending to one edge thereof and being detachably engageable with the bolts, the bolts having heads to bear against the third mentioned bar, wedges slidable transversely between the two first mentioned bars, the two first mentioned bars having channels receiving 70 the wedges, the bolts being disposed immediately adjacent the wedges, and a draft bar attached to the smaller ends of the wedges.

In testimony that I claim the foregoing 75 as my own, I have hereto affixed my signature in the presence of two witnesses.

THOMAS DE WITT RIVERS.
